(57) **CLAIM**

The ornamental design for a high bay LED light fixture, as shown and described.

DESCRIPTION

FIG. 1 is a perspective view of the high bay LED light fixture, showing the new design;

FIG. 2 is an end elevation of the high bay LED light fixture, enlarged relative to the view shown in FIG. 1, an opposing end elevation of the high bay LED light fixture being identical;

FIG. 3 is a side elevation of the high bay LED light fixture, an opposing side elevation of the high bay LED light fixture being a mirror image thereof;

FIG. 4 is a top plan view of the high bay LED light fixture;

FIG. 5 is a bottom plan view of the high bay LED light fixture of FIG. 1; and,

FIG. 6 is a bottom perspective view of the high bay LED light fixture.

In FIG. 1, FIG. 3, FIG. 4, FIG. 5 and FIG. 6, breaks and an accompanying bracket indicate that the fixture has no specific length, and dashed lines indicate environmental structure that forms no part of the claimed design.
